UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

DIAL-LOCK.

1,395,844.

Specification of Letters Patent. Patented Nov. 1, 1921.

Application filed March 25, 1921. Serial No. 455,465.

To all whom it may concern:

Be it known that I, ROLLIN C. LEWIS, a citizen of the United States, and a resident of Stamford, in the county of Fairfield and 5 State of Connecticut, have invented certain new and useful Improvements in Dial-Locks; and I do hereby declare the following to be a full, clear, and exact description of the invention, such as will enable others skilled 10 in the art to which it appertains to make and use the same.

This invention relates to an improvement in dial locks in which a spindle connects the dial with the disk tumbler driving cam.

15 One method of attacking such a lock is to remove the dial and drive the spindle inwardly to force the driving cam against the tumblers carried by the curb and thus detach the curb and its associated tumblers.

20 The object of the invention is to so connect the spindle and driving cam, that any force applied to the spindle tending to drive it inwardly, will disconnect it from the cam thus making it impossible to actuate the 25 tumblers from the outside.

With this object in view my invention consists in the parts and combination of parts as will be more fully explained and pointed out in the claims.

30 In the accompanying drawings, Figure 1 is a view in section through a lock case showing the tumbler, driving cam and part of the spindle; Fig. 2 is a view in elevation of the spindle and driving cam and Fig. 3 is 35 a view showing the spindle disconnected from the driving cam.

5 represents the lock case, 6 the curb having a centrally located sleeve 7 on which the tumblers 8 are mounted and secured and 9 is 40 the driving cam adapted to drive or turn the tumblers 8 in the usual and well known manner. This driving cam is provided with a centrally located hollow hub provided internally with teeth extending lengthwise 45 thereof and adapted to intermesh with similarly arranged teeth 10 formed at the front end of the cam center 11, as shown in Fig. 3. This cam center 11 is screwed and keyed 50 to the spindle 12 so that it turns with the latter, and the spindle is in turn designed to be connected at its outer end with a dial, not shown.

With this construction it will be seen that, when the spindle is turned by the dial, the

driving cam will be turned with the same 55 and manipulate the tumblers in the ordinary and well known manner to release and retract the bolt. If however an attempt be made to open the door by removing the dial and forcing the spindle rearwardly, 60 which is one method of attacking locks of this type, the spindle will be forced out of engagement with the driving cam thus leaving the latter idle or floating and incapable of actuating the tumblers and destroying 65 all means of operating the lock.

In order to prevent the curb from being dislodged by the spindle, I prefer to provide the curb with an opening in line with the sleeve 7 and spindle, which hole is normally 70 closed by a cap 7^a held in place by friction. With this construction it will be seen that if the spindle be driven back to the curb it will dislodge the cap and pass through without detaching the curb. 75

It is evident that changes may be made in the details without departing from the spirit of my invention which consists of means connecting the driving cam and spindle, so that in the event any attempt be made 80 to release the bolt by forcing the spindle inwardly, the spindle will be disengaged from the driving cam thus leaving the latter in position to prevent the operation of the fence. 85

Having fully described my invention what I claim as new and desire to secure by Letters-Patent, is:—

1. In a dial lock, the combination of a spindle, tumblers and a driving cam for the 90 tumblers, the spindle and cam having interlocking connections whereby the cam will be rotated by the spindle, but will be disconnected therefrom when the spindle is forced inwardly. 95

2. In a dial lock, the combination of a spindle, tumblers and a driving cam, the cam and spindle having intermeshing projections whereby the cam will be rotated by the spindle, but which will permit of disengagement of the parts when the spindle is forced inwardly. 100

3. In a dial lock the combination of a spindle, tumblers and a driving cam for the latter, the spindle having teeth extending in 105 the direction of its length and meshing with teeth in the driving cam whereby the latter may be rotated by the spindle, but will be

disconnected therefrom if the spindle be forced inwardly.

4. In a dial lock, the combination of a spindle, tumblers, a driving cam for the latter, and a cam center rigidly secured to the inner end of the spindle, the said cam center provided at its front end with teeth adapted to intermesh with similarly shaped teeth in the hub of the cam, whereby the latter may be rotated by the spindle, but will

be disconnected from said spindle if the latter be forced inwardly.

In testimony whereof, I have signed this specification in the presence of two subscribing witnesses.
